US00D773036S

(12) **United States Design Patent** (10) Patent No.: **US D773,036 S**
 Thorgaard et al. (45) Date of Patent: **** Nov. 29, 2016**

(54) **OXYGEN MASK**

(71) Applicant: **REGION NORDJYLLAND, AALBORG UNIVERSITETSHOSPITAL**, Aalborg (DK)

(72) Inventors: **Per Thorgaard**, Aalborg (DK); **Pernille Woller Jensen**, Hjørring (DK)

(73) Assignee: **Region Nordjylland, Aalborg Universitetshospital** (DK)

(**) Term: **15 Years**

(21) Appl. No.: **35/500,153**

(22) Filed: **Sep. 2, 2015**

(80) **Hague Agreement Data**

Int. Filing Date: **Sep. 2, 2015**

Int. Reg. No.: **DM/087484**

Int. Reg. Date: **Sep. 2, 2015**

Int. Reg. Pub. Date: **Sep. 25, 2015**

(30) **Foreign Application Priority Data**

Mar. 2, 2015 (EM) 002644179

(51) **LOC (10) Cl.** **29-02**

(52) **U.S. Cl.**

USPC **D24/110.1**

CPC **A62B 18/02** (2013.01)

(58) **Field of Classification Search**

USPC 128/206.21-207.18; D24/110-110.6

CPC A61M 16/0616; A61M 16/0633;

A61M 16/06; A61M 16/0666; A61M 16/0683
